ATTORNEY

UNITED STATES PATENT OFFICE.

LEONORA WOLLE, OF ROCKDALE, TEXAS.

TATTING-SHUTTLE.

1,345,303.

Specification of Letters Patent. Patented June 29, 1920.

Application filed March 30, 1920. Serial No. 369,915.

To all whom it may concern:

Be it known that I, LEONORA WOLLE, a citizen of the United States, residing at Rockdale, in the county of Milam and State of Texas, have invented new and useful Improvements in Tatting-Shuttles, of which the following is a specification.

One object of my present invention is the provision of a multiple yarn tatting shuttle—*i. e.*, a tatting shuttle comprising two or more shuttle units detachably connected together so that all the shuttle units may be used as a single unitary device; each of the shuttle units being designed to carry an individually colored yarn, the shuttle units being detachably connected together so that different combinations may be used in a single device, and tension means for the bobbins of the units being provided to prevent too free turning of the bobbins when desired.

To the attainment of the foregoing, the invention consists in the improvement as hereinafter described and definitely claimed.

25 In the accompanying drawings:

Figure 1 is an edge elevation of one compound shuttle or shuttle device constructed in accordance with my invention.

30 Fig. 2 is an enlarged transverse section showing the manner in which I prefer to detachably connect the shuttle units together.

Fig. 3 is a detail view illustrative of the spring-strip complementary to one bobbin.

35 Fig. 4 is a view of a modification.

Similar numerals designate corresponding parts in Figs. 1 to 3 to which reference will first be had.

Each of the shuttle units is designed to 40 carry a yarn 1, and it will be understood that the said yarns are to be of different colors. It will also be understood that each unit comprises two side members 2, an interposed rotary bobbin 3 and a spring-strip 45 complementary to the bobbin; and said spring-strip 4 being designed to maintain the yarns of different colors evenly as to length.

Each spring-strip 4 is connected at one 50 end to one member 2 and is provided at its

opposite end with a projection 4^a which works through an aperture 4^b in the member and exerts yielding pressure against the adjacent bobbin 3.

The shuttle units are detachably connected together in side by side opposed relation, so that neither of the said units will interfere with the use of the other. The said detachable connection is effected through the medium of a snap-fastener 5, 60 and from this it follows that by the exercise of a little stress, one unit may be readily detached from the other and may as readily be attached to such other without any liability whatever of the units becoming 65 casually disconnected incidental to the manipulation and use of the device.

Manifestly when desired the shuttle units may be marketed separately and may be connected together by the purchaser and 70 user in different combinations, according to the number of differently colored yarns that it is desired to use.

In the modification shown in Fig. 4 two units with side members 2 are detachably 75 connected by snap fasteners 5 to an intermediate unit having side members 2^a. The outer units are of the same construction as the units of Figs. 1 to 3. The intermediate unit, however, is not equipped with a bobbin.

Having described my invention, what I claim and desire to secure by Letters-Patent, is:

1. A tatting shuttle comprising tatting 85 shuttle units detachably connected together in opposed side by side relation and each having a rotary bobbin.

2. A tatting shuttle comprising tatting shuttle units detachably connected together 90 in opposed side by side relation; each of said units having side members and rotary bobbin between said side members and also having on one side member a spring-strip provided with a projection arranged to 95 work through an aperture in the side member and bear against the bobbin.

In testimony whereof I affix my signature.

LEONORA WOLLE.
